CLAIM

We claim the ornamental design for a hand-held electronic device cover, as shown and described.

DESCRIPTION

FIG. 1 is a front perspective view of a hand-held electronic device cover;

FIG. 2 is a front elevational view of a hand-held electronic device cover;

FIG. 3 is a back elevational view of a hand-held electronic device cover;

FIG. 4 is a left side elevational view of a hand-held electronic device cover;

FIG. 5 is a right side elevational view of a hand-held electronic device cover;

FIG. 6 is a bottom plan view thereof; and,

FIG. 7 is a top plan view thereof.
